SAMUEL GALBRAITH, OF NEW ORLEANS, LOUISIANA.

Letters Patent No. 72,012, dated December 10, 1867.

IMPROVED DEVICE FOR HITCHING HORSES.

The Schedule referred to in these Letters Patent and making part of the same.

TO ALL WHOM IT MAY CONCERN:

Be it known that I, SAMUEL GALBRAITH, of New Orleans, in the parish of Orleans, and State of Louisiana, have invented a new and improved Device for Hitching Horses; and I do hereby declare the following to be a full, clear, and exact description of the same, reference being had to the accompanying drawing forming part of this specification, which drawing represents a perspective view of my invention.

This invention is a neat, cheap, and durable device, designed to be attached to halters used in hitching horses, mules, &c., to prevent their being thrown, hung, or injured.

In the drawing, A represents a ring, of metal or other suitable substance, which is to receive and hold one end of the halter, and B represents another ring of the same size and similar material, to which to attach another end of the halter. Intermediate between the rings A B are pivoted two double curved jaws C C, pivoted at c, and having their ends next to the ring B connected together by a rod, R, to the centre of which the ring B is hinged, as shown at h. The rod R is an instrument composed of a central tube, t, in each end of which closely fits and slides a short rod, r, connected with the end of the jaws C C. Between the inner ends of the rods r r, inside of the tube t, is a spring, s, operating against the rods r r. The jaws C C may be made each to resemble in shape the letter S, and be crossed at c, in which case the spring s must be attached to the ends of the rods r r, and operate to draw them together, so as to keep the ends c' c' of the jaws C C tightly closed; or the jaws may resemble the figure 3 in shape, being pivoted as before, but not crossed, in which case the spring s must be made to push the rods apart, and thus close the ends c' c' firmly together. The spring s must be made of sufficient rigidity and strength to keep the ends c' c' firmly clasped together, unless when operated upon by some extraordinary force, and in the latter case to yield, unclasp the ends c' c', and let the halter and ring A escape. The rods r r may be attached to the jaws C C, so as to form a joint or hinge, as shown at i i.

One of these devices is to be attached to the halter at some point near the horse's head, the halter being divided into two parts for that purpose, and this apparatus connecting the parts, one part being fastened by the ring A, and the other at the ring B. Another of these devices may be, in a similar manner, fixed to the halter or bridle at the throat-latch; and still another may be fixed to the head-stall. If three are thus used, one at the forehead, another under the throat, and the other forming part of the halter-strap, which is used to fasten the horse, it will be impossible for the animal ever to be in any way injured by reason of twisting the halter, catching his foot in it, or by any of the accidents that destroy so many fine horses in consequence of tying them with halters or ropes. The apparatus is so simple and cheap that every owner of a horse or mule can provide himself with it, and thus effectually insure his stock against a very dangerous hazard.

Having thus described my invention, what I claim as new, and desire to secure by Letters Patent, is—

The device above described, consisting of the rings A and B, and the pivoted curved jaws C C, meeting at one extremity at c' c', and connected at the other by means of the rods r r, and spring s, working in the tube t, substantially as and for the purpose specified.

To the above specification of my invention I have signed my hand, this 3d day of October, 1867.

SAM'L GALBRAITH.
